UNITED STATES PATENT OFFICE.

GEORGE ALBERT FANJOY, OF FREEPORT, NEW YORK.

COMBINATION FOLDING COT.

1,185,989.

Specification of Letters Patent. Patented June 6, 1916.

Application filed July 21, 1915. Serial No. 41,114.

To all whom it may concern:

Be it known that I, GEORGE A. FANJOY, a citizen of the United States, and a resident of Freeport, in the county of Nassau and State of New York, have invented a new and Improved Combination Folding Cot, of which the following is a clear, full, and exact description.

This invention relates to cots and particularly to a combination folding cot and has for an object the provision of an improved arrangement whereby the device may be used as a cot either of the ordinary type or may be used as a folding addition to a cot or support of any suitable kind.

Another object in view is to provide a cot which may be locked in an unfolded position so as to act as an ordinary cot or bed.

A further object of the invention is to provide a cot construction with a central section and folding end sections, together with a support for each section, the end supports being extensible whereby either or both ends of the cot may be raised at any desired angle.

Another object is to produce a folding cot structure which may be provided with supporting legs or may be arranged upon a cot or bed of ordinary construction, the parts being so positioned and constructed as to allow either end to be raised pivotally for providing a raised support for the head or feet of the patient.

In the accompanying drawings:—Figure 1 is a top plan view of a cot embodying the invention; Fig. 2 is a section through Fig. 1 approximately on line 2—2; Fig. 3 is a side view of the cot shown in Fig. 1, one end being shown raised; Fig. 4 is a detail perspective view of one of the end bars or frame members of the cot; Fig. 5 is a detail perspective view of part of one of the side members; Fig. 6 is a detail fragmentary perspective view of the locking device for holding the legs in position; Fig. 7 is a detail perspective view of the sliding connection between the parts of each of the extension legs; Fig. 8 is a side view, with certain parts broken away, of a slightly modified form of the invention which may be applied to an ordinary cot or bed; Fig. 9 is a detail fragmentary perspective view of one corner of the construction shown in Fig. 8; Fig. 10 is a detail fragmentary perspective view of one of the supporting braces shown in Figs. 8 and 9.

Referring to the accompanying drawings

by numerals, 1 indicates a set of springs of any desired kind provided with a frame 2. Adjacent the springs 1 is a second set of springs 3 provided with a frame 4, while adjacent the springs 3 is a third set of springs 5 provided with a frame 6. All of these frames are connected together as shown in Fig. 1 so that the frames may hinge at their point of connection with the frame 4. The means for connecting the frames together may be a cable or wire 7 or other suitable means which will allow the springs 1 and 5 to be raised and lowered pivotally. The pivotal points of these springs are in line with the pivotal points 8 and 9 of the frames 10, 11 and 12. The frame 11, as shown in Figs. 1 and 5, is provided with hinge members 13 and 14 and a central enlarged portion 15 which is provided with an aperture 16 formed with notches 17 and 18, whereby the locking member 19 may be forced therethrough and turned for locking the respective legs 20 in position. The member 19 is constructed as shown in Fig. 6, namely, with a bottom plate 21, an upstanding member 22 which fits into the apertures 16 and notches 17 and 18, and a thumb member 23 which is adapted to be turned to such a position as to be arranged transversely of the notches 17 and 18, as shown at one side of the structure disclosed in Fig. 1. This will lock the parts together including locking the springs 1, 3 and 5 in position. There is a locking member 19 at each end of the frame 11 and a locking member 19 at each corner of the frames 10 and 12, as clearly shown in Fig. 1, all of these locking members being of identical construction so that the description of locking member 19 will equally apply for these particular members.

The frame 10 is formed from a pair of bars 24 which are connected with the hinge members 13 of frame 11 by a suitable pintle and to which is connected a transverse end bar 25. End bar 25, as shown in Fig. 4, is provided with openings in the end similar to the apertures 16 and notches 17 and 18 so as to receive the two locking members 19. The bars 24 are each provided with an upstanding flange 26 which has apertures therein adjacent the outer end whereby the various projections 27 on the ends of bar 25 may be passed through the flange 26 and thus allow a firmer connection of the parts. Frame 12 is made in a similar

2

manner to frame 10 so that an additional description thereof will not be necessary. It will be observed that the bars 24 are provided with turned-over or hinged portions 13' so as to receive the same pintle that is passed through the hinge members 13, whereby the parts are properly hinged together and in alignment with the frame 4. The legs 20 have rigidly secured thereto an arc-shaped brace 28 which engages the lower face of the frame 11 so as to hold the same normally level, the parts of frame 11 being held together by a suitable transverse bar 29, which bar is locked in position by the locking members 19. By providing the particular construction and arrangement of locking members 19 as described the parts of the cot may be assembled and disassembled at any time.

20 At each corner of the cot is arranged a leg 30. Each of the legs 30 is connected with a plate 21, as shown in Fig. 6, by a suitable hinge structure 31. The leg structure 30 is provided with a main section 32 which normally extends vertically as shown in Fig. 2, and a hinge section 33 which is normally folded though the same may be extended as shown in Fig. 3 so as to pivotally raise at an angle one of the frames 10 or 12 according to which particular leg is operated. The sections 32 and 33 are hinged together at 34 and normally held in folded position as shown in Fig. 2 by a spring 35 fitting in a suitable notch 36 in the extreme outer end of section 33. A spring 37 presses against a sliding plate 38 for normally holding the same in an outward position, as shown in Fig. 2. When it is desired to lengthen or straighten out all of the parts of leg 30 the same are arranged as shown at the right in Fig. 3 and the plate 38 is moved downwardly so as to overlap part of the section 32. Plate 38 is provided with turned over ears 39, as shown in Fig. 7, so as to present a guide for retaining the plate in position on section 33, and also with an aperture 40 and notches 41 and 42, whereby a button 43 may be passed through the aperture and then turned for locking the parts in an extended position, as shown at the right in Fig. 3. In order that the section 32 may always extend substantially at right angles to the frame 10 or 12 as the case may be, a catch or brace 44 is provided which extends through a suitable notch 45 in the section 32, and a cutaway portion 46 is utilized as a stop. The catch or brace 44 is pivotally mounted at 47 on a brace 48 rigidly secured to the frame 10 or 12 as the case may be so as to properly support the catch 44. A spring 49 acts on the catch 44 for holding the same engaged, as shown in Fig. 2. In the case it should be desired to fold up the cot 65 for transportation without taking the same

to pieces, catch 44 is disengaged manually and also section 33 is disengaged from spring 35 and these parts arranged in parallel relationship with the frame 10 or 12. If desired, the legs could be removed when preparing the cot for transportation.

The cot is designed to be used in hospitals and other places where injured people or invalids are being cared for, and in order to accommodate people of this character a cot has been arranged so that the legs at either end may be folded or may be extended so that either end of the cot may be raised, or if desired both ends may be raised.

In some instances it is found desirable to provide a structure which will allow either end or both ends of the cot to be raised when using all of the parts shown in Fig. 2. If desired, the legs may be entirely eliminated and other attachments secured as shown in Figs. 8 to 10, whereby the device may be adapted for cots now commonly used or beds of any kind. When the structure in Fig. 8 is used the same is placed directly on the cot and then used as desired. In this form of the invention side members 50 are provided which extend from one end to the other of the device and are connected together by transverse end members 51 held in place by lugs 52 projecting from the various braces 53. When the braces 53 are in operation they are arranged as shown in Fig. 9, a spring 54 holding the parts in their proper relative positions. The upper end of brace 53 is hinged to a plate 55 by a suitable hinge, said plate having connected therewith a locking member 19, as shown in Fig. 6, which locking member passes through the side bar 24 and the end bar 25 in a similar manner to that shown in Fig. 1. When either of the frames 10 or 12 is lowered the same assumes the position shown at the right in Fig. 8, the end bar being entirely removed. The frames 10, 11 and 12 in Fig. 8 are identical with those in Fig. 1 and therefore will need no additional description, these parts being normally mounted on the side plates 50 and end plates 51 and associated with the braces 53 and associated members so as to adapt the springs and supporting frames to an ordinary cot or an ordinary bed.

What I claim is:—

1. In a folding cot of the character described, a body provided with a central section, a pair of end sections, a spring for each of said sections, a pair of button structures for each section for clamping the parts together and said springs to the respective sections, the buttons of one section being interchangeable with the buttons of the other sections, a supporting member for the central section, and adjustable supporting members for the end sections, said last men-

120

125

130

tioned supporting members being designed to produce any desired angle on said end sections.

2. In a folding cot of the character described, a body provided with pivotally mounted end sections and a pair of supports for each end section, each of said supports comprising a plate rigidly secured in position, a depending member hinged to said plate, said depending member having a button arranged therein and a slot, a hinged section connected with said depending member, a spring catch for normally holding said hinged section in a folded position, a sleeve mounted on said hinged section and adapted to slide over the depending member, said sleeve having an opening therein adapted to accommodate said button, said button being formed with a head adapted to straddle said opening, and a pivotally mounted catch arranged to extend through the slot in the depending member for locking the same in a depending upright position.

3. In a folding cot of the character de-

scribed, a body provided with a central section and end sections hinged to the central section, all of said sections having transverse members provided at each end with a round aperture and radiating notches extending from the aperture, a clamping member for each aperture having arms, the respective clamping members extending through said apertures and through said notches when being mounted in position, said arms being adapted to be turned to a position away from the notches whereby said members are locked in position, said clamping members being interchangeable and independent means for supporting each of said end sections and said central section.

In testimony whereof I have signed my name to this specification in the presence of two subscribing witnesses.

GEORGE ALBERT FANJOY.
